Primary Examiner — George D Kirschbaum*Assistant Examiner* — Clese Moore, Jr.(74) *Attorney, Agent, or Firm* — Leanne Taveggia Farrell; Westman, Champlin & Koehler, P.A.(57) **CLAIM**

The ornamental design for a display fixture, as shown and described.

DESCRIPTION

FIG. 1 is a perspective view of a display fixture showing my new design;

FIG. 2 is a front view thereof;

FIG. 3 is a back view thereof;

FIG. 4 is a right side view thereof, the left side view being a mirror image; and,

FIG. 5 is a bottom view thereof.

The dash-dash-dash broken lines shown illustrate portions of the display fixture and form no part of the claimed design. The dash-dot-dash broken lines shown represent boundaries of the claim and form no part of the claimed design.
